UNITED STATES PATENT OFFICE.

HAMILTON W. BINGHAM, OF LANCASTER, PENNSYLVANIA, ASSIGNOR OF ONE-HALF TO MILTON H. HARTMAN, OF SAME PLACE.

DESIGN FOR A TOOTH-PICK CASE.

SPECIFICATION forming part of Design No. 22,505, dated June 6, 1893.

Application filed March 13, 1893. Serial No. 465,830. Term of patent 3½ years.

To all whom it may concern:

Be it known that I, HAMILTON W. BINGHAM, a citizen of the United States, residing at Lancaster, in the county of Lancaster and State of Pennsylvania, have invented and produced a new and original Design for a Tooth-Pick Case, of which the following is a specification, reference being had to the accompanying drawing, forming part thereof, in which is shown a face view of a tooth-pick case embodying my design.

The leading feature of my design consists of a tooth-pick case, which, when viewed from the side, represents the body of a man clothed in an antiquated coat, and a head in profile appearing in proper position above the body.

A is the coat clothing the body and extending down to a point between the hips and knees and having a line drawn around the same set in from the edge of the back and bottom and forming a border a, the body of

the coat and the border being smooth surfaces. A pocket flap a' is shown at or near the hip, and there extends up the front of the coat a lapel a², back of which appears a row 25 of buttons a³.

D is the head, having long hair hanging down behind and a hat, F, thereon with the rim turned up against the crown; and C is a ruffle protruding from the coat beneath the 30 chin.

B represents the legs, and E the arms, the legs and arms being, however, a minor and unessential consideration.

What I claim is—

The design for a tooth-pick case, substantially as herein shown and described.
